UNITED STATES PATENT OFFICE.

BONAPART SCHUTZ, OF HILLVIEW, ILLINOIS.

CAR DOOR.

Application filed October 20, 1921. Serial No. 508,990.

To all whom it may concern:

Be it known that I, BONAPART SCHUTZ, a citizen of the United States, residing at Hillview, in the county of Greene and State 5 of Illinois, have invented certain new and useful Improvements in Car Doors; and I do hereby declare the following to be a full, clear, and exact description of the invention, such as will enable others skilled in 10 the art to which it appertains to make and use the same.

The present invention relates to freight car doors, and more especially to such doors of cars intended for grain, sand and similar 15 materials.

It is the object of the invention to provide a door construction to be disposed within the door opening of the car for retaining the grain, sand or similar material, without 20 the necessity of nailing boards across the door opening as customary, thereby saving expense and trouble as well as damage to the door frame, and providing for the convenient positioning of the door in the opening 25 and the discharge of the material.

Another object is to provide novel means for mounting the door whereby the lower portion thereof can swing outwardly for the discharge of the material, and also enabling the door to be raised and swung out 30 of the way when not in use.

The invention also has for an object the improvement of the construction to enhance the utility and efficiency of the door.

With the foregoing and other objects in view, which will be apparent as the description proceeds, the invention resides in the construction and arrangement of parts, as 35 hereinafter described and claimed, it being understood that changes can be made within the scope of what is claimed, without departing from the spirit of the invention.

The invention is illustrated in the accompanying drawings, wherein—

45 Figure 1 is a face view of the door.

Fig. 2 is a vertical section on the line 2—2 of Fig. 1.

Fig. 3 is a vertical section on the same line showing the door sections raised and 50 swung inwardly.

Fig. 4 is an enlarged section on the line 4—4 of Fig. 1.

Fig. 5 is an enlarged section on the line 5—5 of Fig. 1.

55 The door frame of the car wall has the posts 7 and 8 and the sill 9, and the door is

composed of the lower and upper sections 10 and 11, respectively. The lower section 10 is of greater height than the upper section, and said sections are of a size to fit snugly 60 within the door opening with the upper section resting on the lower one, for retaining the material in the car body.

In order to mount the door sections for vertical and swinging movements in the 65 door opening, vertical guide bars 12 are secured to the posts 7 and 8, preferably flush with the sides thereof which face one another, said bars having ears 13 at their upper and lower ends secured to the posts, 70 and ears 14 intermediate their ends also secured to said posts. The bars 12 have the longitudinal slots 15 the lower portions of which are vertical, and plates 16 are secured to the inner or rear surfaces of the 75 door sections adjacent to the upper edges thereof and have trunnions or pivot studs 17 projecting from the vertical edges of the door sections and extending within the slots 15, for guiding the door sections for up and 80 down movement and permitting said sections to swing inwardly and outwardly about the horizontal axes of said trunnions. Channel binding members 18 are preferably secured on the vertical edges of the door 85 sections, and the plates 16 extend across said members. The door posts are also preferably formed with grooves 19 behind the slots 15 for receiving the trunnions 17. The bars 12 extend from the lintel of the 90 door frame to a point between the ends of the posts, inasmuch as said bars need not extend but a slight distance below the trunnions 17 of the lower door section 10.

In order to fasten the door sections in 95 closed position, latch bolts 20 are slidable in barrels 21 secured to the outer sides of the door sections adjacent to the end edges thereof, to enter holes in the door posts when the door sections are in position, as 100 seen in Figs. 1 and 2. The latch bolts 20 have finger pieces 22 for conveniently sliding said bolts and holding them in either position.

The lower door section has additional 105 latching means for convenience in releasing the lower section or portion of the door to start the discharge of the material. Thus, latch bolts 23 are slidable in barrels or guides 24 secured to the outer side of the 110 door section 10 at the vertical edges thereof, to enter holes or sockets in the door posts,

and the bolts 23, are connected by links 25 with a hand lever 26 disposed between the vertical edges of the door on the outer side thereof. The links 25 have rows of apertures 27 for the engagement of the pivots 28 which connect said links and lever, to provide for adjustments, and enabling the latching device to be applied to doors of different widths. The lever 26 is fulcrumed on a stud 29 of a fulcrum member 30 having a base flange 31 secured to the door section 10, as at 32, and a bolt 33 extends through said door section and member 30 for clamping the intermediate portion of a bar 34 against the stud 29, to hold the lever thereon. The bar 34 is bent in the form of a bow and has its ends secured, as at 35, to the door section 10 at the opposite sides of the member 30. The bar 34 forms a guard and brace for the lever 26 and member 30, and also retains said lever on said member. A segment bar 36 is secured at its ends, as at 37, to the door section 10 and the upper handle end of the lever 26 projects upwardly behind said bar for retaining said lever in place. The bar has a series of apertures 38 for receiving a pin or key 39 used in holding the lever 26 in position. The pin or key 39 is preferably connected loosely to the lever 26 by a chain 40 to prevent the loss of said key or pin. This enables the lever 26 to be secured or locked, for holding the latch bolts 23 in projected position.

The door section 10 is provided at its outer side with suitable hand holds 41 for convenience in raising said door section.

Stops 42 are secured to the posts 7 and 8 for limiting the outward swinging movement of the door section 10 when it is swung open in starting the discharge of the material.

U-shaped members or keepers 43 are secured to the outer side of the door sections adjacent to the lower edges thereof, for the engagement of suspension hooks 44 pivoted to a rafter 45 or other overhead support in the car, thereby enabling the door sections to be supported in raised inwardly-swinged position, as seen in Fig. 3. The bills of the hooks are engageable in the members 43, to prevent accidental disconnection of the door sections from the hooks. The bars 12 have notches 46 near their upper ends extending from the slots 15 for receiving the trunnions 17 when the door sections are raised, to thereby support said door sections in connection with the hooks 44.

In using the door, the sections thereof are lowered into position and the latch bolts 20 and 23 are projected into the holes in the door posts, for holding the door firmly in place, and the material can be run into the car over the door, there being an opening above the door for that purpose. After the

car is filled, the ordinary outer door (not shown) can be closed and sealed, and such outer door is opened prior to the opening of the inner grain door. To start the discharge of the material, the latch bolts 20 of the lower door section are first released, and the pin or key 39 is disengaged from the lever 26. Then, by swinging said lever, the latch bolts 23 can be simultaneously retracted from the door posts, thereby releasing the lower door section, and the pressure of the material against same from the inside will swing said door section outwardly, thereby starting the discharge of the material over the sill 9. The stops 42 will limit the outwardly swinging movement of said door section, to prevent injury to the operator, as well as restricting the flow of material. After the door sections are relieved of pressure from the material within the car, said door sections can be raised and moved out of the way. The latch bolts 20 of the upper door section 11 are first released from the door posts, and the section 11 is slid upwardly and its trunnions 17 moved into the upper notches 46. The door section 11 is then swung inwardly and upwardly and engaged by the corresponding hook 44. The lower door section 10 is then similarly raised and its trunnions 17 moved into the lower notches 46, after which the door section 10 is swung inwardly and upwardly and engaged by the other hook 44. The door sections are thus supported overhead until again needed.

Having thus described the invention, what is claimed as new is:—

A door construction comprising a door frame having posts, said posts having substantially vertical slots in their adjacent sides between their outer and inner sides, upper and lower door sections to seat one on the other, said door sections being disposed between said posts with their ends in abutting relation with the adjacent sides of said posts, trunnions projecting from the vertical edges of each door section below the upper edge thereof and working in said slots, said door sections, when released, being slidable vertically and swingable outwardly and inwardly in the frame between said posts, means carried by each door section to engage said posts for holding the door section in closed position against movement vertically, inwardly or outwardly, and means for supporting the door sections one above the other when slid upwardly and swung inwardly.

In testimony whereof I have signed my name to this specification in the presence of two subscribing witnesses.

BONAPART SCHUTZ.
